WITNESS:

UNITED STATES PATENT OFFICE.

GEORGE R. PYPER, OF SALT LAKE CITY, UTAH, ASSIGNOR TO THE PYPER ANIMATED SIGN COMPANY, OF SALT LAKE CITY, UTAH, A CORPORATION OF UTAH.

DESIGN FOR AN ALPHABET OF SIGN-LETTERS.

58,256.

Specification for Design. Patented June 28, 1921.

Application filed March 12, 1920. Serial No. 365,327. Term of patent 14 years.

To all whom it may concern:

Be it known that I, GEORGE R. PYPER, a citizen of the United States, residing at Salt Lake City, in the county of Salt Lake and State of Utah, have invented a new, original, and ornamental Design for an Alphabet of Sign-Letters, of which the following is a specification, reference being had to the accompanying drawings, forming a part thereof.

The figure is a plan view showing my new design.

I claim:

An ornamental design for an alphabet of sign letters, as shown.

GEORGE R. PYPER.

Witness:

BENNETT S. JONES.
